UNITED STATES PATENT OFFICE

2,462,487

APPARATUS FOR FORMING FELT

Ivor Griffith, Elkins Park, Pa., and Alfred P. Huchberger, New York, N. Y., assignors to The Frank H. Lee Company, Danbury, Conn., a corporation of Connecticut

Application December 28, 1945, Serial No. 637,737

2 Claims. (Cl. 19—144)

1

The present invention relates to a new method of forming felt from fibers such as fur or wool or the like and particularly to such a method in which an electrostatic type of precipitation is utilized to deposit the loose fibers upon a surface as, for example, upon the type of cone normally used in the formation of hat bats.

At the present time it is customary to deposit fur upon a cone by inducing a suction through perforations in the cone to draw the fur onto the cone. This method is in many ways unsatisfactory, one of its major objections being the large amount of power required to operate the suction pumps for this operation.

By our improved method the fur is caused to take a charge and is then attracted to an oppositely charged surface upon which it is deposited, deposition being very uniform and forming a felt structure, which after further processing yields an extremely uniform felt.

It is an object of the invention to provide a method of depositing fibers to be felted upon a surface to form the normal hat bat which will later be shrunk in any known manner to produce a hat.

It is another object of the invention to provide a method of accomplishing this result in which electrostatic means are used to cause the deposition and no suction is required.

It is a further object of the invention to provide such a means of depositing fibers to be felted upon a cone or the like in which the fibers become charged and are impelled to the oppositely charged cone without subsequently dropping from the cone due to the loss of their charge. We have found that by a proper arrangement of point discharge electrodes the air surrounding the fur fibers can be constantly ionized and therefore the fibers retain their charges and thus are caused to remain on the cone once they have been deposited.

Other objects and features of the invention will be apparent when the following description is considered in connection with the annexed drawings, in which—

Figure 1 is an illustrative diagram showing the action of a point electrode and an oppositely charged plate when fibers are blown into the field or fields existing between the point and the plate;

Figure 2 is a plan view of one embodiment of our invention showing means for blowing the fur into the field of ionization and causing the fur to be deposited upon a cone; and

2

Figure 3 is a side elevation of the apparatus of Figure 2.

Referring now to the drawings there is shown in Figure 1 a pointed electrode 10 and a plate 11. 5 If the point and plate have applied to them a voltage in the neighborhood of 60,000 to 100,000 volts and if they be so charged in air a corona discharge occurs from the point. The corona gives rise to a stream of ions having a charge of like polarity to that of the point. The ions are then impelled by reason of the electrostatic field existing between the point 10 and the plate 11 toward the plate. Then any small particles such as 15, as for example, fibers in the path of the ion current are charged by these ions and as a result the fibers are attracted to the plate 11 with appreciable force.

Once the particles or fibers reach the plate the charge will tend to leak off and go to the plate. 20 This tendency is counteracted by the continuous stream of ions supplied by the point 10 so that the particles adhere to the plate as long as the potential difference between the point 10 and the plate 11 is maintained.

25 The principle of operation as disclosed in Figure 1 is shown in Figure 2 as applied to the deposition of fibers upon a cone such as is normally used in the first process in the making of felt hats.

30 Fur or other fibers are deposited on a belt 12 (Figures 2 and 3) and conveyed by that belt to a pair of rollers 13 which deposit them upon a rotating picker 14 which separates the fibers and delivers them into the housing 15 through which 35 they are blown by an air blast produced by any suitably driven fan 16.

Mounted along the top and bottom of the nozzle or housing member 15, near its open end, 40 are rows of electrodes 17 which are pointed electrodes similar to the electrode 10 discussed in connection with Figure 1. The housing is made of insulating material so that there is no charge upon it. A positive potential is applied to the points 17 and a ground or negative potential to 45 a cone 18 which cone, as has clearly been shown in the drawings, is in this particular instance horizontally mounted and arranged to be rotated at a relatively slow speed by motor 19.

Points 17 are, as has been indicated above, 50 charged to a high positive potential which may be in the neighborhood of 60,000 volts relative to ground and the cone 18 is connected to ground. Thus, there exists between the points 17 and the cone 18 a pair of zones, one above and one beneath the nozzle member 15, of ionized air, and

the fibers, which are blown through the housing, become charged and are attracted to the cone 18. Since the cone is rotating, the fibers are deposited thereon in an even layer and the effect of the ionization and the attraction of the fibers to the cone 18, results in these fibers adhering to the cone and in their intermeshing with each other and lying relatively flat upon the surface of the cone so that a slight felting action occurs, this action being sufficient to provide a hat bat which can be handled and may be removed from the cone prior to any wetting operation.

We do not know the exact reason that the fibers felt to a greater extent than is the case when the normal method of suction through the cone is utilized, but whatever the explanation it is true that the felting action is greater than when suction methods are used. Furthermore, there is but a slight reduction of the attractive effect as the felt is built up to its desired thickness, using our method, whereas with the old suction method, once the perforations in the cone are covered, the suction becomes relatively ineffective, and many of the fur fibers are lost because the attractive power, that is the suction, is diminished to such an extent that additional fibers are not attracted to the cone.

In addition to the advantages pointed out above, our method utilizes very little current and is extremely economical of power, and in fact reduces the power requirements to approximately $\frac{1}{10}$ of those of the older suction method of forming felt hat bats. Additionally, the cones utilized in our method may be imperforate and may be formed, for example, of sheet material whereas the cones in the old method must be perforated, and are more difficult to manufacture and consequently more expensive.

While we have described a preferred embodiment of our invention it will be understood that other embodiments thereof may be devised without departure from the spirit of our invention. Therefore, we wish to be limited not by the foregoing description, which was given for purposes of illustration only, but solely by the appended claims.

What is claimed is:

- 5 1. In a device for depositing feltable fibers upon a cone, in combination, a rotating cone, a generally rectangular nozzle mounted adjacent thereto, with the generatrix of the cone parallel to the longer dimension of the rectangular nozzle, means for discharging feltable fibers through said nozzle, and a plurality of point electrodes insulatingly mounted on said nozzle in rows, one on either side of the exterior of the nozzle, the points of said electrodes terminating short of the nozzle mouth, said electrodes and said cone being oppositely charged to a high potential whereby fibers emerging from said nozzle are placed in streams of ionized air and are thereby charged 10 15 with the same charge as said electrodes and attracted to the oppositely charged cone.
2. In a device for depositing feltable fibers upon a cone, in combination, a rotating cone, a generally rectangular nozzle mounted adjacent thereto, with the generatrix of the cone parallel 20 25 to the longer dimension of the rectangular nozzle, means for conveying feltable fibers through said nozzle and discharging said fibers from said nozzle mouth, a plurality of point electrodes insulatingly mounted on said nozzle in rows, one on either side of the exterior of the nozzle, the points of said electrodes terminating short of the nozzle mouth, said electrodes and said cone being oppositely charged to a high potential whereby 30 35 fibers emerging from said nozzle are placed in streams of ionized air and are thereby charged with the same charge as said electrodes and attracted to the oppositely charged cone.

IVOR GRIFFITH.
